INVENTOR

UNITED STATES PATENT OFFICE.

ROBERT JOYCE, OF PHILADELPHIA, PENNSYLVANIA.

DESIGN FOR A BURNER FOR GAS-IRONS.

44,208.

Specification for Design.

Patented June 17, 1913.

Application filed December 28, 1912. Serial No. 739,123. Term of patent 14 years.

To all whom it may concern:

Be it known that I, ROBERT JOYCE, a citizen of the United States, residing in the city and county of Philadelphia and State of Pennsylvania, have invented a new, original, and ornamental Design for Burners for Gas-Irons, of which the following is a specification, reference being had to the accompanying drawing, forming part thereof.

Figure 1 represents a perspective view of

a burner showing my design. Fig. 2 represents a side elevation thereof. Fig. 3 represents a front elevation.

I claim:

The ornamental design for a burner for gas irons, as shown.

ROBERT JOYCE.
